UNITED STATES PATENT OFFICE

90,636

DESIGN FOR A BUILDING

Alma F. Tall, Ruth, Nev., assignor of forty
per cent to Horace G. Lathrop, Ruth, Nev.

Application June 24, 1933. Serial No. 48,516

Term of patent 7 years

To all whom it may concern:

Be it known that I, ALMA F. TALL, a citizen of the United States, residing at Ruth, in the county of White Pine and State of Nevada, have invented a new, original, and ornamental Design for a Building, reference being had to the accompanying drawing, forming part thereof.

In the drawing:

Figure 1 is a view in side elevation of the building showing my new design;

Figure 2 is a view in front elevation of the building;

Figure 3 is a view in rear elevation of the same.

I claim:

The ornamental design for a building, as shown.

ALMA F. TALL.
